BERRY BOX

Charles Augustin and Thomas P. Carroll,
St. Louis, Mo.

Application February 15, 1932, Serial No. 593,059

3 Claims. (Cl. 229—23)

This invention relates to new and useful improvements in berry boxes or containers. These boxes are generally made with sloping side walls, the upper end of the boxes being open and larger than the bottom of the boxes. They are used as containers for various commodities. Where they are used as berry boxes, they are formed with perforate side walls and bottoms to permit circulation of air therethrough. The empty boxes are shipped from the factory to the field or other location where they are to be used. As the boxes even when nested together occupy considerable shipping space, it is desirable to ship them flat in which case they take up very little space and can be easily handled.

It is one of the objects of the present invention to provide a berry box which can be shipped and stored in flat condition and which can be readily assembled at the field, for instance, by an inexperienced person and without the use of adhesive or staples or other securing means and machinery.

Other objects of the invention are to provide a collapsible berry box consisting of two separable members, the outer one comprising a band, the ends of which are secured together to form a downwardly tapering box open at top and bottom and the inner member or liner comprising four side walls or flaps arranged in cruciform shape and formed integral with the central piece which forms the bottom of the box. Certain of the side walls are provided with means whereby the inner and outer members are locked together when in assembled relation.

Further objects of the invention are to provide a collapsible box consisting of outer and inner members, the outer member comprising a band having its ends secured together and being scored to form sloping side walls, the inner member being in cruciform shape and scored and adapted to be nested within the outer member, the sloping side walls of the outer member and the sloping edges of the flaps of the inner member serving to hold the latter in position within said outer member, said inner member being provided with outwardly extending dove-tailed tongues and the corresponding side walls of the outer member being provided with suitable apertures for receiving said tongues whereby said members are locked together.

Still further objects of the invention are to provide a collapsible berry box comprising an outer and an inner member arranged in nested position, the side walls of said members being provided with coinciding tongues which can be

pressed or distorted to occupy positions beyond the planes of the respective side walls, thereby preventing the disassembly of said members.

With these and other objects in view, our invention consists in certain novel features of construction and arrangement of parts, hereinafter more fully described and claimed, and illustrated in the accompanying drawing, in which—

Figure 1 is a front elevational view of our improved berry box.

Figure 2 is a vertical cross section taken on line 2—2 of Figure 1.

Figure 3 is a reduced plan view of the outer member before the ends thereof are secured together.

Figure 4 is a top plan view of the outer member with the ends secured together and ready for shipment.

Figure 5 is a top plan view of the inner member.

Referring by numerals to the accompanying drawing, 10 indicates an outer or box member and 11 the inner or lining member. The outer member 10 is in the form of a strip and is scored along transverse lines, as indicated by 12, thereby dividing said member into four panels 14 which when said member 10 is folded form the outer side walls of the box. As shown, these lines 12 converge symmetrically, thereby forming the panels 14 of trapezoid shape. One end 30 of member 10 has formed integral therewith a flap 15 which when member 10 is folded along lines 12 is glued to the opposite end of said member, thereby retaining the latter in box-shape form.

Certain of said panels 14 are provided with apertures 16 and certain other of said panels are provided near their lower ends with openings 17 and near their upper ends with downwardly presented tongues 18. The latter are cut but are not pressed out and normally remain in the same panel with the respective panel 14.

The inner section or lining member 11 is formed of cruciform shape having a central panel 19 and outwardly projecting panels 20. These 45 projecting panels are bendable upwardly along score lines 21 to form the inner walls of the box. The side edges 22 of the wall panels 20 are disposed obliquely and converge inwardly substantially on the same angle as lines 12. Consequently panels 20 are formed trapezoid and are of substantially the same width at their outer ends A as the outer ends B of panels 14. The depth of panels 20 is less than the depth of panel 14.

Consequently when the formed inner member 11 is inserted into the box member 10, said inner or lining member is supported in position by the converging walls of the outer member with the bottom 19 of said lining member spaced upwardly from the lower end of said outer member (see Figs. 1 and 2).

The bottom wall 19 is provided with a plurality of apertures 24 through which air is admitted from the bottom of member 10 into the box formed by said lining member 11.

One pair of the opposed side wall panels 20 is formed each with spaced apertures 25. These apertures are so spaced as to coincide with apertures 16 of the corresponding panels of outer member 10 when said lining member 11 is placed in the latter. They are of larger diameter than apertures 16 in order to take care of any slight irregularities in said panels or the spacing of the apertures. By means of these aligned apertures 16 and 25, air is admitted into the box through said apertured side walls. The other pair of opposed side walls is formed near their inner ends adjacent to score lines 21 with tongues 26. These tongues are formed dove-tailed, being considerably wider at their outer ends, as indicated at 26a, than at their junction with the bottom wall 19. The respective score lines 21 do not extend across the tongues 26 but terminate adjacent to the narrow end thereof so that when the respective panels 20 are bent upwardly, said tongues 26 project outwardly from said bottom wall 19.

Each aperture 17 is formed at each side with an elongated extension or slot 17a, the combined length of which is slightly greater than the width of the outer end 26a of the respective tongue so that the latter can be readily inserted therethrough. The lower end of each aperture 40 is curved downwardly as indicated at 17b and when the lining member 11 is properly positioned in the outer member 10 the bottom wall 19 and tongues 26 are disposed in a horizontal plane below the slots 17a, and the neck or narrow portions of tongues 26 rest in the arcuate or restricted portions 17b as shown in Figures 1 and 2. This arrangement locks tongues 26 in position and prevents the removal thereof from said apertures. The lowermost portion of each arcuate opening 17b is left open and it forms a ventilating opening through which air is admitted near the bottom wall 19 whereupon the air can then enter the interior of the box through apertures 24. The upper end of each aperture 17 is curved upwardly as indicated at 17c and permits air to enter the box through the ventilating openings thus formed.

One pair of panels 20 is formed near each upper or outer end with a semi-circular tongue 27. These tongues are identical in shape and size with tongues 18. When the inner or lining member 11 is placed in the outer member 10, tongues 27 are in register with tongues 18. By pressing against tongues 18 of the outer member 10 said tongues 18 and tongues 27 are pressed inwardly as shown in Figure 2. This positions the ends of tongues 18 into the same plane with walls 20 or beyond said plane so that the inner member 11 is held against upward movement and is locked in position (see Fig. 2). Thus the two members 10 and 11 are locked together and cannot be accidentally displaced. Tongues 26 form additional support for the inner or lining member 11 and limits the downward movement thereof.

Members 10 and 11 are shipped and stored in

knock-down condition or flat, as illustrated in Figures 4 and 5, and, therefore, occupy very little space. They can be readily inserted together simply by opening the box member 10 and bending upwardly the panels 20 of member 11 and inserting the latter in member 10.

We claim:

1. A collapsible berry box of the class described comprising in combination an outer member formed of a single strip of sheet material scored transversely to provide four side wall panels, and an inner member substantially cruciform in shape and having a central bottom panel and four side panels, said side panels being bendable upwardly whereby said inner member fits into said outer member when the latter is formed box-shape, one pair of the opposed panels of said outer member being formed near their lower ends with apertures, each having an arcuate lower end and a comparatively wide horizontally disposed upper portion, and a pair of tongues formed integral with the bottom wall of said inner member, said tongues being formed dove-tailed and insertable through the wide portions of said apertures and having their neck portions resting in the lower restricted ends of said apertures, thereby locking said members together and limiting the downward movement of said inner member in said outer member.

2. A collapsible berry box of the class described comprising in combination an outer member formed of a single strip of sheet material scored transversely on converging lines to provide four trapezoidal wall panels, the ends of said strip being secured together to form downwardly tapering open-ended box, and a lining member of cruciform shape having four projecting trapezoidal panels and a central panel, said projecting panels being bendable upwardly to fit said inner member within said outer member, one pair of opposed walls of said outer member being formed near each lower end with an aperture having curved upper and lower ends and having curved upper and lower ends and having elongated centrally and horizontally disposed extensions, and a pair of dove-tailed tongues cut out from the corresponding wall panels of said inner member and formed integral with the bottom thereof, said tongues being insertable through said central portions of said apertures and being adapted to have their narrow portions resting in the lower curved ends of said apertures to lock said inner member within said outer member, said curved upper and lower ends forming openings through which air is admitted into the box and near the bottom wall of said inner member, said bottom wall being perforated to permit air to pass upwardly into said box.

3. A collapsible berry box of the class described comprising in combination an outer member formed of a single strip of sheet material scored transversely on converging lines to provide four trapezoidal wall panels, the ends of said strip being secured together to form downwardly tapering open-ended box, a lining member of cruciform shape having four projecting trapezoidal panels and a central panel, said projecting panels being bendable upwardly to form inner walls of the box and said central panel forming the bottom wall thereof, one pair of the opposed walls of said outer member being provided near their upper ends with downwardly presented cut-out tongues and the corresponding side wall panels of the inner member being provided with coinciding cut-out portions whereby said tongues

can be pressed inwardly into the plane of said cut-out portions, thereby locking said box members together, there being formed in one pair of the opposed walls of said outer member near the lower ends thereof apertures which are comparatively narrow and wider at their centers and have curved upper and lower ends, and dovetailed tongues cut out from the corresponding side wall panels of said inner member and formed integral with the bottom wall thereof, which tongues are insertable through said wide por-

tions of said apertures and are adapted to have their neck portions resting in the lower restricted ends of said apertures to form supporting means for said inner member and locking said members together, said bottom member being formed with apertures and the apertures in the side wall panels of said outer member forming openings through which air is admitted into said box. 5
